UNITED STATES PATENT OFFICE

2,481,943

SEAT AND LEG REST ARRANGEMENT

Frank L. Murphy and Carl H. Apel, Chicago, Ill.,
assignors to Pullman-Standard Car Manufacturing Company, Chicago, Ill., a corporation of Delaware

Application September 28, 1944, Serial No. 556,134

11 Claims. (Cl. 155—8)

1

The present invention relates to an improved seat arrangement for use in a railway passenger car and the like. The so-called day coach is becoming increasingly popular for over-night travel, and many efforts have been made to improve the comfort of the coach seat. In accordance with the present invention, the seat is convertible in effect into a chaise-longue. This is done by the use of a foot and leg rest that may be used in conjunction with the seat.

It is one object of the present invention to provide in combination with a coach seat a foot and leg rest that is readily adaptable for use in a railroad passenger car or the like to convert the seat into a considerably more comfortable accommodation, particularly for night use. It is a further object of the invention to provide extra leg room between the seats without decreasing the seating capacity of the car and thereby add materially to the comfort of the passengers.

Other objects and advantages will become apparent from the following description and the drawings, in which

Fig. 1 is a perspective view of one embodiment of the invention showing three double seat units arranged in tandem and further showing the foot and leg rest both in open and closed positions;

Fig. 2 is a vertical sectional view taken through the back of one of the coach seats and the foot and leg rest showing the latter in its horizontal operative position;

Fig. 3 is a fragmentary sectional view taken on the line 3—3 of Fig. 6;

Fig. 4 is a vertical sectional view corresponding to Fig. 2 but showing the foot and leg rest in its inoperative position;

Fig. 5 is an enlarged, fragmentary, vertical sectional view taken at the base of the seat back shown in Fig. 4 illustrating in particular the hinge mechanism and counter-balancing spring forming part of the foot and leg rest;

Fig. 6 is a vertical, transverse sectional view through the foot and leg rest taken on the line 6—6 of Fig. 2;

Fig. 7 is an elevational view of the seat back shown partially in section, the view being taken in a direction corresponding to 7—7 of Fig. 2;

Fig. 8 is a transverse sectional view taken on the line 8—8 of Fig. 7;

Fig. 9 is an enlarged detailed view of the supporting connecting rod shown in Fig. 2; and

Fig. 10 is an enlarged, fragmentary, sectional detail view showing in elevation the counter-

2

balancing spring used in conjunction with the foot and leg rest.

For purposes of illustration, one embodiment of the invention is shown and described.

5 Referring, for example, to Fig. 1, the invention may take the form of a foot and leg rest, generally indicated at 25, fastened at one end to a seat generally indicated at 26 and disposed closely adjacent to the front of a second seat generally indicated at 26a. The seats 26 and 26a are identical, each consisting generally of a seat base portion 27 supporting one or more seat cushions 28 and a pair of seat backs 29. As shown in Fig. 2, the seat backs 29 are adjustable 10 between a forward or upright position shown in solid lines in Fig. 2 to a reclining position 29a indicated in broken lines.

The seat cushion portion 28 and back 29 per 15 se do not constitute structural details of the present invention, and therefore only sufficient structure will be described to bring out the relationship between these members and the foot and leg rest 25. Referring particularly to Figs. 2, 4, 20 5, and 7, the seat back 29 is mounted on a shaft 45 about which the seat back 29 is moved from its upright position, shown in solid lines in Fig. 2, to its reclining position, shown in broken lines at 29a.

The foot and leg rest 25 is movable between 25 an open or operative position, shown in Fig. 1, between seats 26 and 26a to a closed or inoperative position in the back 29 of the seat as shown in seat 26a. When in its open position, the foot and leg rest 25 is supported on a supporting leg member 30 (Fig. 1), and when in this open position the top surface of the foot and leg rest 25 in effect forms a continuation of the top surface of the adjacent seat cushion 28. Thus, the foot and leg rest 25 cooperates with the adjacent seat cushion 28 to form the horizontal seat portion of a chaise-longue. The adjacent back member 29 may then be adjusted, as previously described, to fit the required needs of the seat occupant.

Referring to Figs. 2, 4, and 6, the foot and leg rest 25 comprises a frame, generally indicated at 31, consisting of a pair of front and back framing members 38 and 39, respectively, and a pair of side framing members 40 and 41, all of which, for purposes of illustration, are shown as made of wood. Across the bottom of the space surrounded by these framing members is a bottom panel 42, for example, of pressed wood. This panel 42 is fastened to all of the aforementioned framing members. A suitable upholstering material 43 fills the space surrounded by the fram-

ing members and extends sufficiently above the framing members to suitably cushion to top portion of the foot and leg rest. A covering 44 of fabric, for example, completely surrounds the framing members and covers the bottom panel 42 and the top surfaces of the upholstery material 43.

The foot and leg rest 25 is mounted adjacent to its one edge on the shaft 45 by means of two or more hinge members 46, one of which is shown, for example, in Fig. 2.

An upright foot support member, generally indicated at 47, extends upwardly from the foot and leg rest 25 and consists of a vertical portion 48 and a horizontal portion 49 (see Fig. 2), both of which portions are covered by carpeting 50. The horizontal portion 49 of the foot support 47 has an arced portion 52 fitting over the portion of the hinge member 46 that is journaled on the shaft 45. Adjacent to the lower edge of the seat back 29 is a plate member 53 fastened to the seat back, as indicated at 54, and provided with a concave portion 53a. The plate member further includes an upwardly extending flange 56 fastened to the seat back frame and a downwardly projecting portion 57 extending considerably below the shaft 45 about which the hinge member 46 is journaled. The concave portion 53a of the plate 53 is located directly adjacent to the shaft 45 and the curved portion 52 of the foot support 47 extends partially into the curved portion 53a of the plate 53.

The foot and leg rest 25 is movable about the shaft 45 from its open, substantially horizontal position, shown in Fig. 2, to its inoperative position shown in Fig. 4 inside a recess 55 provided in the back of seat back 29. During this rotating motion, the curved portion 52 of the foot rest 47 revolves inside the concave portion 53a of plate 53. This curved portion 52 of the foot support 47 serves as a safety guard and finish plate covering the fulcrumed portion of the hinge member 46.

Again referring to Fig. 6, the supporting leg 30 comprises a horizontal floor engaging member 30a and a pair of uprights 58 and 59, the free ends of which uprights are pivotally mounted as at 61 at opposite sides to the foot and leg rest 25. When in its open position, the foot and leg rest 25 is thus partially supported on the floor by the supporting leg 30. A connecting rod 64 at each side of the foot and leg rest 25 is pivotally secured at 60 to one of the uprights 58 or 59. Each connecting rod 64 extends along one side of the foot and leg rest 25 and is secured at its free end to a bracket 62 mounted on a base frame 63 forming part of the seat member 26. Upstanding posts or pedestals 63a mounted on the base frame 63 are disposed at each side of the seat back 29 and the free ends of the shaft 45 (see Fig. 7) are supported on these pedestals 63a.

Each bracket 62 is provided with a vertical slot 62a in which the connecting rod 64 is free to move. As shown in Fig. 7, each connecting rod 64 is mounted on a pin 65 passing through the slot 62a in bracket 62, and a spring 66 is fastened at one end to the pin 65 and at the other to the seat base frame 63.

As shown in Figs. 2 and 9, for example, when the foot and leg rest 25 is in its open, operative position and the connecting rod 64 is disposed substantially horizontally, the connecting rod 64 rests at the bottom of the slot 62a. As the foot and leg rest 25 is moved toward its closed position in the recess 55 in the seat back (see Fig. 2), it rotates, as previously mentioned, about the shaft

45. Since the connecting rod 64 is fastened to the bracket 62 at a position below the shaft 45, the connecting rod 64 applies a torque on the supporting leg 30 to rotate it about its pivot points 61 until the supporting leg 30 assumes a position shown in broken lines in Fig. 4. Before the foot and leg rest 25 reaches its fully closed position in the recess 55, the supporting leg 30 has reached its fully closed position, shown in Fig. 4, and therefore during the last portion of the movement of the foot and leg rest 25 into the recess 55 the connecting rod 64 moves upwardly in the slot 62a, placing the spring 66 in tension and thereby holding the leg 30 closed. At the time the supporting leg 30 is in its open position shown in Fig. 2, the spring 66 is in its normal relaxed position, holding the connecting rod 64 in the lower part of the slot 62a, thereby preventing the connecting rod from rattling while the car is in motion.

As shown in the embodiment of the invention, the seat back 29 may be adjustable between an upright and a reclining position, though obviously such a condition is not necessary as the present invention is equally applicable to other types of seats. It is also permissible that each seat unit 26 be adapted to rotate or swivel about a vertical axis (not shown), as is the case in many of the seat units in use today in modern railroad cars, so that the seat unit, if desired, may be turned 90 degrees to face the car windows, or through 180 degrees to face the opposite direction. Obviously, the foot and leg rest under these circumstances would rotate with the seat upon which it is mounted.

As shown in Fig. 2, the seat portion 28 may normally assume the position shown by dotted lines 28a and may be adjustable to the solid line position against the foot and leg rest.

The present invention provides a greatly improved arrangement for adapting a day-coach seat for night use. Obviously, its use is not limited to night use, however, as the foot and leg rest is very easily and quickly moved from one position to another. In the embodiment of the invention, the foot and leg rest when moved to its inoperative position entirely clears the floor space between the seats. Only a very simple operation is required to convert the seat into a comfortable chaise-longue at any time. The presence of the recess in the back of the seat permits the foot and leg rest, while in its inoperative position, to repose as far as possible from the next seat behind, thus providing the maximum amount of free floor space between seats.

Though only one specific embodiment of the invention is disclosed, it is recognized that many other modifications may be made without departing from the scope of the invention.

We claim:

1. For use with a second seat to form a chaise longue, the combination with a seat of a back rest having an elongated recess in the back thereof extending substantially throughout the height and width of the back rest, a foot and leg rest substantially coextensive in length and width with the recess adapted to fit into the recess, means pivotally mounting the foot and leg rest with respect to the back rest adjacent to the bottom of said recess so that the foot and leg rest can be moved from a closed, inoperative position in the recess to an open, operative position where it extends rearwardly from the back rest.

2. In combination with a seat adapted to be used with the seat portion of a second seat to form a chaise longue where the second seat is placed behind the first seat, a back rest, a recess entering the back face of the back rest, a foot and leg rest adapted to fit into the recess, means pivotally mounting the foot and leg rest with respect to the back rest adjacent to the bottom of the recess so that the foot and leg rest can be moved from a closed, inoperative position in the recess to an open, operative position where it extends rearwardly with respect to the back rest, the outermost edge of the extended foot and leg rest being approximately at the height of the second seat portion, a retractable, supporting leg on the foot and leg rest, and means retracting the supporting leg as the foot and leg rest is moved to its inoperative position.

3. A chaise longue combination comprising a pair of seats spaced apart and arranged in tandem, a seat portion and a back rest for each seat, the forward back rest having an elongated recess in the back face thereof extending substantially throughout the height and width of the back rest, a foot and leg rest, means pivotally mounting the foot and leg rest with respect to the forward back rest adjacent to the bottom of the recess so that the foot and leg rest can be moved from a closed, inoperative position in the recess to an open, operative position where it extends rearwardly from the forward back rest to a position closely adjacent to the forward edge of the seat portion of the second seat, the foot and leg rest substantially filling the recess when disposed in closed, inoperative position.

4. In combination with a seat, a back rest having cushion means on one side thereof and relatively planar edge portions on the other side thereof, an elongated recess in the back rest extending from the plane of the edge portions inwardly toward the cushion side and being substantially coextensive with the height and width of the back rest, a foot and leg rest having cushion means on one side thereof and a relatively planar face on the other side thereof, means pivotally mounting the foot and leg rest with respect to the back rest adjacent to the bottom of the recess so that the foot and leg rest can be moved from a closed, inoperative position in the recess to an open, operative position where it extends rearwardly from the back rest, the foot and leg rest substantially filling the recess when disposed in closed, inoperative position with the cushion means on the foot and leg rest disposed adjacent to the cushion means on the back rest and with the planar face of the foot and leg rest disposed substantially flush with the planar face of the back rest.

5. In combination with a seat, a back rest, a foot and leg rest comprising an elongated leg supporting member substantially coextensive with the height of the back rest and a foot support adjacent to one end of the leg supporting member and disposed at an abrupt angle with respect to the leg supporting member and extending therefrom, an attachment adjacent to the lower edge of the back rest, the foot and leg rest being pivotally attached to the last mentioned support and disposed adjacent to the rear side of the back rest so that the foot and leg rest can be moved from a closed inoperative position against and substantially in contact with the back rest to an open operative position where it extends rearwardly from the back rest, the

foot support being adapted to project forwardly of the general plane of the back rest when the foot and leg rest is disposed in its closed inoperative position, and means providing clearance at the lower end of the back rest for the foot supporting member.

6. A chaise longue combination comprising a pair of seats spaced apart and arranged in tandem, a seat portion and a back rest for each seat, the forward back rest having an elongated recess in the back face thereof extending substantially throughout the height and width of the back rest, a foot and leg rest, means pivotally mounting the foot and leg rest with respect to the forward back rest adjacent to the bottom of the recess so that the foot and leg rest can be moved from a closed, inoperative position in the recess to an open, operative position where it extends rearwardly from the forward back rest to a position closely adjacent to the forward edge of the seat portion of the second seat, the foot and leg rest substantially filling the recess when disposed in closed, inoperative position; and means supporting the foot and leg rest in operative position.

7. A chaise longue combination comprising a pair of seats spaced apart and arranged in tandem, a seat portion and a back rest for each seat, a foot and leg rest of a length and width sufficient to provide a continuous leg supporting area corresponding in length substantially with the spacing between the seats and in width being substantially as wide as an individual seat, the forward back rest having an elongated recess in the back face thereof having a height and width substantially corresponding with the length and width of the foot and leg rest, means pivotally mounting the foot and leg rest with respect to the forward back rest adjacent to the bottom of the recess so that the foot and leg rest can be moved from a closed, inoperative position in the recess to an open, operative position, the lower end of the recess being disposed below the upper face of the seat portion of the rear seat, and the foot and leg rest when in operative position extending from the lower end of the recess rearwardly in a diagonally upward direction to a position closely adjacent to the forward edge of the seat portion of the rear seat.

8. A seat adapted to be used with a seat portion of a second seat to form a chaise longue when the second seat is spaced in tandem arrangement behind the first seat, comprising a seat portion and a back rest, a foot and leg rest of a length and width sufficient to provide a continuous leg supporting area corresponding in length substantially with the spacing between the seats and in width being substantially as wide as an individual seat, the back rest having an elongated recess in the back face thereof having a height and a width substantially corresponding with the length and width of the foot and leg rest, the lower end of the recess being disposed below the upper face of the seat portion of the second seat, and means pivotally mounting the foot and leg rest with respect to the back rest adjacent to the bottom of the recess so that the foot and leg rest can be moved from a closed, inoperative position in the recess to an open, operative position extending from the lower end of the recess rearwardly in a diagonally upward direction so that it may assume a position with its outer end disposed closely adjacent to the forward edge of the seat portion of the second seat.

9. A seat adapted to be used with a seat portion of a second seat to form a chaise longue when the second seat is spaced in tandem arrangement behind the first seat, comprising a seat portion and a back rest, a foot and leg rest of a length and width sufficient to provide a continuous leg supporting area corresponding in length substantially with the spacing between the seats and in width being substantially as wide as an individual seat, means pivotally mounting the foot and leg rest with respect to the back rest adjacent to the bottom of the back rest so that the foot and leg rest can be moved from an inoperative position against and parallel to the back rest to an operative position extending from the lower end of the back rest rearwardly in a diagonally upward direction so that it may assume a position with its outer end disposed closely adjacent to the forward edge of the seat portion of the second seat, the rear face of the back rest being concave in the region directly above the pivoted edge of the foot and leg rest so as to provide additional foot clearance.

10. In combination with a seat adapted to form a chaise longue with a second seat placed behind the first seat, a seat frame for the first seat, a back rest extending upwardly from the rear edge of said seat frame and pivoted thereto to swing back to reclining position, a foot and leg rest also pivoted to said rear edge of the seat frame of the first seat to swing from a substantially horizontal position to a substantially upright position and having a width corresponding substantially with the width of the back rest and a length corresponding substantially with the spacing between the seats, said foot and leg rest being adapted to be moved from an operative position where it extends rearwardly from the back rest to provide a substantially continuous and unbroken surface throughout its length and width between the first seat and the second seat to an inoperative position where it is disposed closely adjacent to and substantially parallel with the back rest with the upper end of the foot and leg rest disposed closely adjacent to the upper end of the back rest.

11. In combination with a seat adapted to form a chaise longue with a second seat placed behind

5 the first seat, a seat frame for the first seat, a back rest extending upwardly from the rear edge of said seat frame, pivot means connecting the back rest to the seat frame to swing back to reclining position, a foot and leg rest, means pivotally mounting the foot and leg rest to swing about the axis of said named pivot means from a substantially horizontal position to a substantially upright position and having a width corresponding substantially with the width of the back rest and a length corresponding substantially with the spacing between the seats, said foot and leg rest being adapted to be moved from an operative position where it extends rearwardly from the back rest to provide a substantially continuous and unbroken surface throughout its length and width between the first seat and the second seat to an inoperative position where it is disposed closely adjacent to and substantially parallel with the back rest with the upper end of the foot and leg rest disposed closely adjacent to the upper end of the back rest.
